W. J. Ciswell.

Inventor

UNITED STATES PATENT OFFICE.

JOSEPH M. ANGELETTI, OF NEW YORK, N. Y.

TIRE TRIMMER.

1,424,433.

Specification of Letters Patent. Patented Aug. 1, 1922.

Application filed October 10, 1919, Serial No. 329,653. Renewed December 19, 1921. Serial No. 523,589.

To all whom it may concern:

Be it known that I, JOSEPH M. ANGELETTI, a subject of the King of Italy, and a resident of New York, in the county of New York and State of New York, have invented a certain new and useful Improvement in a Tire Trimmer, of which the following is a full, clear, and exact specification.

This invention relates more particularly to a class of devices adapted to be used in conjunction with vehicle tires made of rubber.

During the manufacture of the casings or shoes of commonly used pneumatic tires for vehicle wheels it is customary to provide the inner wall of layers of cloth or canvas or interwoven cord, and on the exterior of the tread portion of each inner wall is a layer of vulcanized rubber. The outer surface 20 part of the rubber layer in many types of casings is formed with protruding shoulders extending lengthwise of the casing in spaced proximity to its clench flanges. When taken from the molds following the vulcanizing process these shoulders of the casing are usually of such irregular or ragged formations that careful trimming is required, in order that the finished casing will be neat and sightly in appearance. According to 30 the present methods in use a great deal of time is consumed and skilled workmanship required to accomplish this class of trimming.

My invention has for its object primarily 35 to provide a device or trimmer designed to overcome these objections by providing a form of blade or cutter having one or more substantially V-shaped cutting edges whereby the irregular parts on the protruding 40 shoulders of the casing may be readily removed, and on the blade at each cutting edge is a guide for causing the blade to be accurately moved during the trimming process as well as serving to prevent accidental 45 cutting or damage to the tire.

Other objects of the invention are to provide a holder on which the blade is removably mounted, and this handle is of an adjustable type so that it may be adjusted to 50 various positions to facilitate the work of trimming; and to provide a trimmer of a simple, efficient and durable construction which may be made in any suitable size.

With these and other objects in view, the 55 invention will be hereinafter more fully de-

scribed with reference to the accompanying drawing forming part of this specification in which similar characters of reference indicate corresponding parts in all the views, and will then be pointed out in the claims 60 at the end of the description.

In the drawing, Figure 1 is a fragmentary view showing portion of the rubber casing of a vehicle tire as well as showing the manner of using one form of trimmer embodying my invention for trimming the casing.

Fig. 2 is an enlarged fragmentary view, partly in detail and partly in section, taken vertically through a portion of the device.

Fig. 3 is a fragmentary detail sectional view taken on the line 3—3 of Fig. 2.

Fig. 4 is an enlarged perspective view of the blade used in the trimmer, and

Fig. 5 is an enlarged fragmentary sectional view taken on the line 5—5 of Fig. 4.

The device or tire trimmer has a blade or cutter 10 which may be of any suitable size and this blade has a flat body part 11 of preferably an approximately rectangular shape, and midway of the lengthwise edges 80 of the body part are notches, as 12 and 13. On the ends of the notched body part of the blade are guides or plates, as 14 and 15, serving to enable the blade to be accurately moved when trimming a tire, as will be hereinafter more fully explained, and these guides are of similar formations. The guides are preferably made integral with the body part 10 by angularly bending the end parts of a flat strip of metal in somewhat a Z-shape. The guides or plates 90 14 and 15 are thereby substantially rectangular, and one of the lengthwise edges of the blade may be notched, as at 16, if desired. At the angles or junctures of the guides with the 95 body part 10 and in the edges of the blade opposite to the notches 16 are cutting edges, as 17 and 18, both of which are preferably in the forms of approximately V-shaped recesses extending crosswise of the blade. The 100 body part 10 of the blade at one of the corners of each of the V-shaped recesses is cut away in an inclined fashion, as at 19, and these inclined parts together with the walls of the recesses are sharpened to keen cutting 105 edges.

In order to allow the blade to be conveniently and properly manipulated for trimming the tire the blade is removably mounted on a holder, as 20. This holder may be 110

of any suitable form, though the one illustrated is composed of a handle 21 of a desired size and shape so that the implement may be easily held in the hand of a person, and in 5 a socket 22 provided in one end of the handle is bolted, as at 23, the tong or tang 24 which extends from a head, as 25. I prefer to make the head and tang of two corresponding flat plates 26 and 27 which are disposed in lapping arrangement, and the head may be somewhat wider than the tang to provide 10 two shoulders 28 and 29 which abut against the end of the handle. The free ends of the parts of the plates 26 and 27 forming the head 25 are bent or struck in opposite directions to each other in the form of a forked end 28^a with a groove 29^a therebetween. The ends of the parts of the plates 28 and 29 forming the tang 24 interiorly of the handle 20 are held together by the bolt 23, and the parts of the plates forming the head 25 adjacent to the fork 28 are screwed or bolted together, as at 30 and 31.

In the groove 29^a between the prongs of 25 the fork 28 is pivoted, at 32, one end of an adjustable clamping element 33 for detachably carrying the blade or cutter 10. This clamping element may be of any suitable shape, though the form shown has a partially 30 circular or disklike end 34 which is the portion of the element pivoted to the fork 28 so that the element may be swung angularly with respect to the holder 20 and handle 21. On the other end of the clamping element 35 are two approximately oval shaped complementary jaws 35 and 36 with a transverse slot 37 midway therebetween, and all of these parts of the clamping element are preferably 40 formed of two corresponding plates 37^a and 38 which are disposed in lapping arrangement. As indicated, the slot 37 may be provided by grooving the opposed central parts of the plates forming the oval jaws 35 and 36, and the circular end of these plates are 45 movably held together by the pivot 32, while in spaced registered pairs of holes 38^a and 38^b in the jaws at the lower and upper edges of the slot 37 are provided removable bolts or screws 39 and 40. The slot 37 is of a 50 width so that the body part 11 of the blade 10 may be removably accommodated therebetween, and the bolts 39 and 40 are spaced apart at a distance so that when the blade is 55 arranged in the slot the notches 12 and 13 of the blade will engage the shanks of the bolts. The blade 10 is applied to the clamping element 33 by removing from the jaws 35 and 36 the bolts 39 and 40. One of the plates 37^a and 38 is swung from the other 60 plate. The blade 10 is arranged in the slot 37 so that the V-shaped cutting edges 17 and 18 are in opposed relation to the handle 21 and so that the notches 12 and 13 are in register with the pairs of holes 38^a and 38^b of 65 jaws 35 and 36. The plates 37 and 38

are then rearranged in lapping positions, and the bolts 39 and 40 are reinserted in the pairs of registered holes, besides being tightened. The blade 10 and the clamping element may then be swung angularly relative 70 to the holder 20, and to limit the angular movement of the clamping element, on the disklike end 34 of the element is a lug 41 which protrudes toward the bottom of the groove 29^a between the prongs of the fork 28. 75 In spaced holes at the lower part of the fork 28 are provided bolts or pins 42 and 43 which are disposed across the groove 29 of the fork so that the lug 41 of the clamping element is movably disposed therebetween. 80 When the blade and the clamping element 33 are swung angularly relative to the holder 20 the lug 41 of the element will contact with one of the pins 42 and 43, and the blade and the element will be 85 held in position to allow a person to conveniently use the implement, as shown in Fig. 1.

In practice the implement is preferably employed for trimming the casing or outer cover, as 44, of pneumatic tires such as are commonly used on automobiles, trucks, motorcycles and the like, many forms of the casings being made with a lengthwise protruding shoulder, as 45, adjacent to each of 95 its clencher flanges, at 46. During the molding and vulcanizing process in making the casing an irregular or ragged edge, as 47, remains on each of the shoulders, and when the implement is employed for trimming 100 the shoulders the clamping element 33 with the blade 10 are usually swung to angular positions relative to the holder 20 and handle 21. By then directing the implement, as illustrated in Fig. 1, the ragged edge of 105 each shoulder of the casing may be readily removed by one of the cutting edges of the blade 10.

In the foregoing description, I have embodied the preferred form of my invention, 110 but I do not wish to be understood as limiting myself thereto, as I am aware that modifications may be made therein without departing from the principle or sacrificing any 115 of the advantages of this invention, therefore I reserve to myself the right to make such changes as fairly fall within the scope thereof.

Having thus described my invention, I claim as new and desire to secure by Let- 120 ters Patent:—

1. In a tire trimmer, the combination with a holder having a forked head with a handle, of two detachably connected clamping plates pivoted between the forks of the head 125 for being swung to angular positions, and a blade having a substantially rectangular body part removably mounted between the clamping plates, said blade having oppositely disposed angularly bent ends with sub- 130

stantially V-shaped notches having cutting edges at the intersections of the body part with the bent ends of the blade.

2. In a tire trimmer, the combination with a holder having a forked head with a handle, of two detachably connected clamping plates pivoted between the forks of the head for being swung to angular positions, and a blade having a substantially rectangular body part removably mounted between the clamping plates, two guide plates protruding angularly in opposite directions from the ends of the body, said blade having in one of its edges two substantially V-shaped cutting edges, one at the intersection of each guide plate with said body part, and stops on the forks of the head for limiting the angular movements of the clamping plates.
3. A tire casing trimmer including a blade provided with a substantially V-shaped recess forming opposed cutting edges, a guide member on said blade and arranged at an angle substantially less than a straight angle to said blade for bearing upon the outer 20 surface of the tire casing between the shoul-
- 25

der and the bead on one side of the casing to guide said blade in trimming said shoulder, and a handle for drawing said blade along the tire casing.

4. A tire casing trimmer including a blade 30 provided with a substantially V-shaped recess forming opposed cutting edges, a guide member on said blade and arranged at an angle substantially less than a straight angle to said blade for bearing upon the outer 35 surface of the tire casing between the shoulder and the bead on one side of the casing to guide said blade in trimming said shoulder, and a handle for drawing said blade along the tire casing, said guide being 40 comparatively thin adjacent the recess so as to provide clearance for the material trimmed from the tire casing.

This specification signed and witnessed this 9th day of October A. D. 1919.
